U.S. Appl. No. 29/673,263, filed Dec. 13, 2018, Brown.

Primary Examiner — Elizabeth A. Albert*(74) Attorney, Agent, or Firm* — Daniel F. Nesbitt; Hasse & Nesbitt LLC(57) **CLAIM**

I claim the ornamental design for a growing tray cover, as shown and described.

DESCRIPTION

FIG. 1 is a top-front perspective view of a growing tray cover, showing the new design;

FIG. 2 is a bottom-rear perspective view thereof;

FIG. 3 is a left side view thereof;

FIG. 4 is a front view thereof;

FIG. 5 is a right side view thereof;

FIG. 6 is a rear view thereof;

FIG. 7 is a top plan view thereof; and,

FIG. 8 is a bottom plan view thereof.

The broken away symbols that consist of solid, straight zigzag lines in FIGS. 1, 2, 3, 5, 7 and 8 indicate that the appearance of any portion of the article between the broken away symbols forms no part of the claimed design.
